KNIFE RACK

Charles A. Ellis, Hamden, Conn., assignor to Sargent & Company, New Haven, Conn., a corporation of Connecticut

Application March 1, 1954, Serial No. 29,262

Term of patent 7 years

(Cl. D44—29)

To all whom it may concern:

Be it known that I, Charles A. Ellis, a citizen of the United States, residing in Hamden, in the county of New Haven and State of Connecticut, have invented a new, original, and ornamental Design for a Knife Rack, of which the following is a specification, reference being had to the accompanying drawing, forming part thereof, in which

Fig. 1 is a top plan view of a knife rack embodying my new design;

Fig. 2 is a front elevational view thereof; and

Fig. 3 is an enlarged end elevational view of the knife rack.

I claim:

The ornamental design for a knife rack, as shown.
